M. S. MATTHEWS

RADIOHORN

Filed May 4, 1925

INVENTOR:
MAX S. MATTHEWS
BY
F. ad. D. Dunn
ATTORNEY.

UNITED STATES PATENT OFFICE.

MAX S. MATTHEWS, OF LOS ANGELES, CALIFORNIA.

DESIGN FOR A RADIOPHORN.

Application filed May 4, 1925. Serial No. 13,315. Term of patent 7 years.

To all whom it may concern:

Be it known that I, MAX S. MATTHEWS, a citizen of the United States, residing at Los Angeles, in the county of Los Angeles and State of California, have invented a new, original, and ornamental Design for a Radiophorn, of which the following is a specification, reference being had to the accompanying drawing, forming part thereof.

The drawing is a perspective elevation of the radio horn showing my new design.

I claim:

The ornamental design for a radiophorn, as shown.

MAX S. MATTHEWS.
